UNITED STATES PATENT OFFICE.

PHILIP DIEHL, OF ELIZABETH, NEW JERSEY, ASSIGNOR TO THE SINGER
MANUFACTURING COMPANY OF NEW JERSEY.

TAKE-UP MECHANISM FOR SEWING-MACHINES.

SPECIFICATION forming part of Letters Patent No. 462,398, dated November 3, 1891.

Application filed June 23, 1891. Serial No. 397,221. (No model.)

To all whom it may concern:

Be it known that I, PHILIP DIEHL, a citizen of the United States, residing at Elizabeth, in the county of Union and State of New Jersey, have invented certain new and useful Improvements in Take-Ups for Sewing-Machines, of which the following is a specification, reference being had therein to the accompanying drawings.

10 My invention has for its object to provide a take-up for sewing-machines which may be operated by a rotating crank-pin and still be properly timed so as to let off the thread slowly and take it up quickly, thereby avoiding the use of a cam-operated take-up and the objectionable wear and friction incidental thereto, while securing all of the advantages thereof as to timing and positive action.

To this end my invention consists of a bell-20 crank lever, one arm of which is jointed to a rotating crank-pin, the other arm of said lever being jointed at its angular portion to one end of a link, the other end of said link being connected with a stationary pivot-pin, all as 25 will hereinafter be more fully set forth.

In the accompanying drawings, Figure 1 is a front elevation of a "Singer" sewing-machine with my improved take-up applied thereto, and with the cap or face-plate of the 30 head removed. Fig. 2 is a view similar to Fig. 1, but with some of the parts in different positions. Fig. 3 is a front end view of the head of the machine, but with certain parts omitted. Fig. 4 is a side view of the machine, 35 partly in section. Fig. 5 is a plan view of the head and forward part of the machine with the frame-work thereof in section. Figs. 6 to 11, inclusive, are detached detail views of parts constituting the take-up and its operating mechanism. Fig. 12 is a detail view illustrating a slight modification.

A denotes the work-plate, and B the bracket-arm, of an ordinary Singer sewing-machine. Journaled in the upper portion of said bracket-arm is a driving-shaft C, provided at its rear end with the usual fly and pulley wheel D, and having at its forward end a crank-disk E, provided with a crank-pin e, to which is connected a pitman f, which serves 45 to operate the needle-bar g. The crank-pin 50

e, as herein shown, has an integral arm or extension e', provided with a second crank-pin e². Pivoted on a pin h, secured in the forward end of the bracket-arm B is a link i, to which is pivotally attached, at its angular or middle portion, a bell-crank lever k, the lower arm of which is jointed to the crank-pin e², and the upper arm of which extends outward and is provided at its free end with a thread-receiving eye k', the said upper arm thus forming the take-up proper.

By constructing the take-up lever in the form of a bell-crank lever and mounting it on a link connected to the stationary part of the machine and then operating it by a rotating crank-pin, the said take-up lever is given a peculiar movement in that it moves bodily up and down with the swinging end of the link by which it is carried, and it is also vibrated on its pivotal connection with said link. As a result of this construction and arrangement of parts the take-up arm of the said lever is caused to descend slowly during about three-quarters of the revolution of its operating crank-pin, and then to quickly ascend during about the remaining quarter of said revolution to perform its take-up movement to tighten the stitch.

Fig. 1 represents the take-up lever at its extreme upper position, and during nearly a half-revolution of the crank-pin from the position shown in Fig. 1 to that indicated in Fig. 3 the take-up lever is descending bodily. Fig. 3 represents the take-up-operating crank-pin at its lower position, from which point it begins to move upward, but in doing so it causes the take-up lever to vibrate on its central pivotal connection with the link, and thus while the operating crank-pin has commenced to ascend, the take-up arm still continues to move downward until it has reached the position shown in Fig. 2. During the next quarter of a revolution, or from the position shown in Fig. 2 to that shown in Fig. 1, the take-up lever has moved upward bodily and is vibrated on its pivot so that the upward movement by the take-up arm of said lever is completed in about one-third of the time occupied by its descent, or during about a quarter-revolution of its operating crank-pin. From this it re-

sults that I am able to secure a properly-timed take-up lever, which will let off the thread slowly during the time the needle-bar is descending and while the shuttle is passing through the loop of needle-thread, and which will then quickly perform its take-up movement to tighten the stitch before the eye of the needle again enters the fabric. Moreover, the positions of the parts are such that at the moment when the stitch is being tightened the take-up-operating crank-pin is passing over the upper part of the circle in which it rotates, and the lower arm of the take-up is nearly vertical. The take-up is at this moment therefore being vibrated on its pivotal connection with the link, thereby affording a strong leverage, so that any desired strength of pull on the thread is afforded without strain on the running parts of the machine. It will thus be apparent that by the simple mechanism above described I am enabled to provide a suitably-timed take-up, which is operated from a rotating crank-pin, and which is therefore well adapted to high speeds as it may be operated with comparatively little power and friction.

The timing of the take-up movements may be varied to adapt my improved take-up for operation in connection with different forms of lower stitch-forming mechanisms from the oscillating shuttle *s*, herein shown, simply by varying the relative position of the stationary pivot to which the link is secured, by changing the length of the lower arm of the take-up, or by changing the position of the take-up-operating crank-pin.

Although I have herein shown a secondary crank-pin for operating my improved take-up

in its particular relation to the shuttle mechanism of a Singer oscillating-shuttle sewing-machine, it will be understood that this secondary crank-pin may not be necessary with some other machines, but that the same crank-pin by which the needle-bar pitman is operated may also serve to operate the take-up, as is shown in Fig. 12, and I do not, therefore, wish to be understood as limiting my invention to the specific arrangement and proportions of parts herein illustrated.

I claim and desire to secure by Letters Patent—

1. A sewing-machine take-up mechanism consisting of a bell-crank lever, one arm of which is provided with a thread-eye, and a link which is pivoted at one end to a stationary part of the machine, and to the other end of which the central or angular portion of said bell-crank lever is jointed, combined with a rotating crank-pin to which the other or lower arm of the said bell-crank lever is connected.
2. In a sewing-machine, the combination, with a rotating crank provided with a secondary or offset crank-pin, of a needle-bar operated by the first-named crank, a bell-crank lever take-up operated by said secondary or offset crank-pin, and a link one end of which is connected to a stationary part of the machine, and to the other end of which the angular or central portion of said take-up lever is pivoted, substantially as set forth.

In testimony whereof I affix my signature in presence of two witnesses.

PHILIP DIEHL.
